UNITED STATES PATENT OFFICE.

EDWARD G. ERNST, OF CLEVELAND, OHIO.

ADDRESSING-MACHINE.

1,149,354.

Specification of Letters Patent. Patented Aug. 10, 1915.

Application filed March 24, 1910. Serial No. 551,246.

To all whom it may concern:

Be it known that I, EDWARD G. ERNST, a citizen of the United States, residing at Cleveland, in the county of Cuyahoga and State of Ohio, have invented a certain new and useful Improvement in Addressing-Machines, of which the following is a full, clear, and exact description.

This invention relates to improvements in printing machines which are organized for the primary purpose of adapting them to print circular letters resembling type written letters.

The object is to provide such machines with means whereby the names and addresses of parties, to whom such letters are to be sent, are printed on the sheets at the same time the letters are printed thereon. Also to provide such machines with means whereby the same names and addresses may be printed in like order upon the envelops in which said circular letters are to be inclosed.

The invention is shown in the drawings applied to such a machine of familiar type.

The invention relates entirely to means by which, as a printing machine is operated, address bearing slugs are carried successively into proper printing relation to the letter form so as to be printed with it by the printing machine; and also to the means by which said slugs will be successively moved into another position where the machine may print said address on an envelop.

The invention embodied in the best form now known to me is hereinafter described and definitely pointed out in the appended claims, and is shown in the accompanying drawings in which—

Figure 1 is a plan view of a machine embodying this invention, partly broken away and showing sections of the frame on the lines 1—1 of Fig. 2. Fig. 2 is a vertical longitudinal section of the machine on the plane of line 2—2 of Fig. 1. The impression roller, however, is shown moved to a different position along the bed and above the address slug. Fig. 3 is a vertical transverse section on the plane of the lines 3—3 of Figs. 1 and 2. Fig. 4 is an enlarged section showing the left hand end of the slide R and a portion of its guideways. Fig. 5 is a similar view of a portion of the guideways near the right hand end thereof, showing the drop in the guides just beyond their printing position. Fig. 6 is an elevation on

enlarged scale of the left end of the elevated platform or guideway upon which the slugs are supported and moved along, a slug being shown thereon. Fig. 7 is a perspective view of the chain trigger which engages and moves the reciprocating cable attached to the reciprocating slide R. Fig. 8 is a perspective view of one of the address slugs.

The printing machine includes a base A and two side frame members B, B', fixed thereto, a bed C, preferably horizontal, on which the type form may be secured, which bed may be vertically adjustable, as, for example, through resting on cams f fixed to two rock shafts F,—said shafts being each provided with an arm f' , and said arms being connected by a link f'' . A crank f^3 on projecting end of one shaft F, Figs. 1 and 2, admits of adjustment by hand. Two chain belts E, E' lie respectively close inside the two frame members B, B'. At one end of the machine these two chain belts run over sprocket wheels g mounted on stud bearing pins g^4 on the inner faces of the two frame members; and at the other end of the machine these two chain belts run over two sprocket wheels g' fixed to a shaft G. An impression roller I is mounted in bearings secured to these two chains, and on its shaft just inside the chains are guide rollers i, i' , which in the upper traverse of the roller ride upon guide rails I', I' suitably supported from the side frame B and beneath the overhanging top flanges b^3 of said frame. See Figs. 2 and 3. A crank J is mounted in one of the side members B of the frame, and has a gear j engaging with a gear g^2 secured to shaft G. When the crank shaft is turned in the proper direction, both chains are caused to move in the direction shown by the arrows on Figs. 1 and 2, and they carry the roller I which is thereby moved over the bed so as to press down upon the type form thereon a sheet of paper laid upon it. In its return movement this roller passes beneath the bed. Commonly an inking ribbon is placed between the type form and the paper so that the letter, printed with the machine described, shall resemble typewritten letters, but that is not involved in this invention and is therefore omitted from the drawing.

The machine as so far described is old; and it is to that machine that my invention is applied as shown in the drawing. It is

to be understood, however, that the invention is not limited to use in connection with this particular machine.

The names and addresses of the parties to whom circular letters are to be sent are on the top surfaces of the address slugs Q. Each slug is provided with depending legs q located preferably near the four corners thereof; and it also has a depending lug q' which may be located in any suitable position, but is preferably placed near one end of the slug and about midway between the sides thereof. These slugs are piled one upon another in a hopper H which is supported on the overhanging end of a transverse bar C' which forms an elevated platform across the bed. The bottom slug is supported by this extension of the bar C'; and the lower edge of the inner wall of the hopper is at such distance above the surface of this bar that the bottom slug, and that only, may be pushed along said bar out of the hopper.

In the top surface of the platform bar are two guide grooves c which extend transversely across the bed in a direction parallel with the type lines in the type form secured to the bed. The characters on these slugs are to be printed when the letters are printed, and therefore the printing surfaces of the type and slugs must be in the same plane. The slugs are made as thin as circumstances will permit, having in mind the use to which they are to be put. The machine is organized to use type of the ordinary sort as to height. Therefore the part of the platform bar lying across the bed on which these slugs rest and move is in a plane above the top of the bed on which the type form is secured. The guide grooves c are in this raised surface. Below this platform top is a recess c' which serves as a guideway for a reciprocating slide R. Through this platform top is a slot c² leading to this recess c',—this slot being parallel with the guide grooves c and in such position that the lug q' of the slug Q will be aligned with it when said slug is resting on said platform with its legs q projecting into the guide grooves c. This slide R is reciprocated to and fro in the guide recess c' by suitable mechanism to be presently described. It carries a bent finger lever T which, when the slide is moving in the direction which carries it away from the hopper, will project its finger up into or through the slot c² to a point where it will engage with the lug q' on the bottom slug, and will thereby move said slug out of the hopper and along the platform to the desired position relative to the type form D. When this slide moves in the reverse direction, this lever is drawn downward so that its finger may pass the bottom slug in the hopper, and then it flies up into the position first de-

scribed so that when again moved in the first named direction the finger will again carry the bottom slug out of the hopper and along said platform. A spring t normally holds this finger lever T in the operative position shown in Fig. 4. A trip lever S is pivoted to the finger lever T, and extends downward alongside of the same and projects below it, being normally held against finger lever T by a light spring s.

On the bed C at the bottom of the recess c' is a short trip rail c⁴. When the slide is moving away from the hopper, pushing the bottom slug out of the hopper and along the platform this trip lever hits the end of said rail and is swung to the left as shown by dotted lines in Fig. 4. This swinging of the trip lever does not effect the position of the finger lever T. When the slide R has carried the trip lever S past the trip rail c⁴, said trip lever flies to the position shown in full lines in Fig. 4. When, now, the slide R moves to the left the trip lever strikes the end of said rail and is thereby rocked and in so rocking it rocks lever T so as to draw its upper finger end down to a plane below the lug q' on the slug resting on the platform. The finger of the lever T therefore passes under the bottom slug in the hopper. Then the lever S passes the end of the trip rail c⁴ and springs s and t return the levers S and T to their positions shown by full lines in Fig. 4. It is evident, therefore, that during each complete movement of the slide R the bottom slug will be drawn from the hopper and moved along to the position it should occupy relative to the type form, and left there; whereupon the slide returns to its starting point ready to move the next slug in the hopper (which is now the bottom slug) in like manner.

If the invention is, as preferably it should be, so constructed as to enable each slug to be printed twice, once on the letter, and once on an envelop, the slide R will carry at its right end another slug-engaging finger lever T', and associated parts like those which have been described. Another trip rail c⁵ is required to engage with the trip lever S' associated with this other finger lever T' and move it in the manner described. The function of this second finger lever T' is to move the slug from the position it occupies when it is printed as a part of the letter, along said platform to a position where it may be printed on an envelop. As the machine shown is organized this latter movement from one printing position to the other is less than the movement required to carry a slug from the hopper to the first mentioned printing position. The distance between the finger levers on the slide R is therefore made shorter than the distance which the slug has to move in going from the hopper to the first printing position.

During the first part of the movement of said slide R, the slug which has been printed as a part of a letter is not moved; but very soon the finger lever T' engages with this slug and thereafter both slugs are moved simultaneously by the two finger levers T and T', and both are carried to the required positions—that is to say, the one drawn from the hopper is moved to the position required relative to the type form, and the other slug is carried to a position where it may conveniently be used for printing an envelop. It will be understood that one passage of the impression roller I over the bed will print both of said slugs, the one on the letter, and the other on the envelop.

It will also be understood that the slug used to head or address a letter on one pass of the impression roll I is next used to address an envelop for that letter on the next pass of the impression roll when another letter having a different address is being printed. In other words, when a letter is being printed an envelop is also being printed with an address to correspond with that of the next preceding letter.

The top surface platform on which the slugs rest is depressed at α^6 just to the right of the position in which the slug is placed for printing an envelop. See Figs. 3 and 5. When, therefore, the next slug is moved along to the envelop printing position, it will push the slug in that position to the right and onto the depressed surface of said platform. This surface is depressed only just a little, but enough to prevent a slug resting upon this surface from being printed when the impression roller moves over the bed. This depressed part of the platform is extended as far as desired to the right and each slug, as it reaches the envelop printing position, pushes the other slugs in advance of it until one by one they are pushed from said platform.

The described mechanism employed to move the slugs is connected with the impression roller so that as the latter is moved the slide R will also move as described. A cable M is fixed at its ends to the ends of the slide R, and said cable runs over guide sheaves N supported by the bed; and one stretch of this cable is parallel and close to the right-side frame member B. To this stretch of the cable a bar O is fixed, which bar extends both above and below said cable. On the lower end of this bar is a guide foot O which carries friction rollers—said foot entering a groove in a rib b projecting from the frame member B, and the rollers passing behind flanges b' which overhang said groove.

A trigger P is pivoted to one link of the chain belt E. This trigger is a bell crank lever, the inner arm p' of which is turned down so as to project into the plane of the

upper end of the bar O, in which position it is held by the engagement of the other arm p' of said trigger with the inner face of the frame member B. It will be understood that in the operation of the machine the chain belts move in the direction indicated by the arrows on Figs. 1 and 2. The trigger is secured to the chain belt E in such position that after the roller I has moved across the form to print the same on a paper, this trigger, when on the upper stretch of the chain, will come against the arm O and will move it and the cable M and the slide R the required distance. This will bring the arm p' of the trigger opposite a recess b² in the inner face of the frame member B near its upper edge, which will permit the trigger to swing back, and its pendent end thereby release and pass the bar O. It is during this movement of the slide R that the slugs are moved from one position to another as described. When the trigger is carried by the lower stretch of the chain belt in the reverse direction, beneath the plane of the bed, the trigger arm p' will, by engaging with the inner face of the frame member B, move the trigger arm p to and will hold it in position for again engaging bar O; whereby the cable M and slide R will be moved in the reverse direction the required distance. Then the trigger arm p', in the lower stretch of the chain, comes opposite another recess b³ in the inner face of the frame member B near its lower edge, which allows the trigger to swing and release the bar O.

Having described my invention, I claim:

1. In a printing machine, the combination of a substantially horizontal type supporting bed having a transverse guide groove, a slug hopper fixed over the grooved part of said bed and adapted to hold a stack of address slugs, reciprocating mechanism for withdrawing the lowest slug from said hopper and moving it horizontally across said bed to a definite printing position and leaving it there for a time, and for subsequently reengaging and moving the same slug still farther across said bed and off the same.

2. In a printing machine, the combination of a substantially horizontal type supporting bed having a transverse guide groove, a slug hopper fixed over the grooved part of said bed, and mechanism for moving the lowest slug in said hopper out of the hopper and transversely of the bed to a definite printing position and leaving it there for a time, and for subsequently reengaging and, moving the same slug a farther distance across said bed to another definite printing position and leaving it there for a time, and for subsequently moving said slug farther across the bed to an inoperative position.

3. In a printing machine, the combination of a substantially horizontal type supporting bed having a transverse slug guide, a

slug hopper fixed to said bed at one side thereof over said guide, a device supported by said bed and movable to and fro across the same and adapted, when moving in one direction to withdraw the lowest slug from said hopper, and to move it horizontally along said guide, an impression roller movable over the bed, and mechanism intermediate of said impression roller and slug moving device for compelling their synchronous movement.

4. In a printing machine, the combination of a type supporting bed, a slug hopper fixed to and located above said bed near one side thereof, a slide supported upon said bed and movable crosswise thereof, a cable fixed at its ends to the ends of said slide, guide sheaves supported by the bed over which said cable runs, an impression roller movable above the bed and lengthwise thereof, mechanism intermediate of said impression roller and said cable, whereby they are connected at intervals to move said slide, a movable slug engaging device carried by said slide, and means for holding said device in a slug engaging position and for releasing it therefrom substantially as specified.

5. In a printing machine, the combination of a type supporting bed, a slug hopper fixed to said bed, a slide supported by the bed and movable to and fro crosswise of the same, a tripable lever carried by said slide, a trip rail, means for holding said lever in operative position to engage the slugs while the slide is moving in one direction over said trip rail, and means coöperating with said trip rail for withdrawing the lever from said operative position when the slide is moving in the contrary direction.

6. In a printing machine, the combination of a bed having a transverse guideway, a surface above said guideway in which is a guide groove, and through which surface is a parallel slot, a hopper fixed above the grooved and slotted part of said bed, a slide moving in said guideway, a finger lever pivoted to said slide, a spring normally holding said finger lever in a position where its end will project into the slot in the bed, a trip lever pivoted to the finger lever, a trip rail below the trip lever, and means for moving said slide backward and forward in said guideway.

55 7. In a printing machine, the combination of a bed adapted to support a type form and carrying a transversely extended raised platform having below its top surface a transverse guideway and having in its top surface a guide groove and having through its top surface a slot, a slide movable in the guideway in said platform, a finger lever movably supported by said slide and projecting upward into said slot, means for holding said finger lever in operative posi-

tion and for releasing it from that position as required, means for causing said slide to move to and fro in its guide-way, and a slug holding hopper fixed above the groove and slotted part of said platform.

8. In a printing machine, the combination of a bed having a transverse guideway, a surface above said guideway in which is a guide groove and through which surface is a parallel slot, a hopper fixed above the grooved and slotted part of said bed; a slide moving in said guideway, a finger lever pivoted to said slide, a spring normally holding said lever in a position where its end will project into said slot in the bed, a trip lever pivoted to the finger lever, a trip rail below the trip lever, a cable fixed to the ends of said slide, guide sheaves fixed to the bed and over which said cable runs, an arm fixed to said cable, a belt arranged with one stretch above the other and with both stretches parallel with the stretch of the cable to which said arm is fixed, a trigger carried by said belt, means for holding it in a position for engaging with said arm and for releasing it from said position.

9. In a printing machine, the combination of a bed having a transverse guide groove, two endless belts which run over and under said bed near the side edges thereof, and an impression roller extended transversely of said bed and mounted in bearings fixed to said two belts, a slug holding hopper fixed over the grooved part of said bed, slug moving means supported by said bed, and means carried by one of said endless belts for moving the slug moving means.

10. In a printing machine, the combination of a frame having two side members, a type supporting bed located between said side members, wheels mounted on said side members, two endless belts located just inside said side members and running over said wheels, and an impression roller mounted in bearings fixed to said belts, a hopper fixed over the bed and adapted to contain a stack of address slugs, means for moving the lowest slug in said hopper out of the same and transversely upon said bed, and a trigger carried by one of said belts and adapted to engage with said slug moving means to operate the same, and means for holding said trigger in operative position and for releasing it as required.

11. In a printing machine, the combination of a bed adapted to support a type form and having a transversely extended guide groove in its top surface, a guideway below said surface and a slot through said surface communicating with said guideway, a slide movable in said guideway, mechanism for moving it to and fro therein, and two levers pivoted to said slide, means independently holding said levers in operative position so that their upper ends will pro-

ject into said slot, a trip lever associated with each of said levers, two trip rails with which said trip levers are adapted to severally engage, and a slug holding hopper 5 fixed to the bed above the grooved and slotted part thereof.

12. In a printing machine, a support having a type form thereon, a rotatable impression roller adapted to move bodily over 10 the type form and in co-action with the printing face thereof, a magazine adapted to contain a plurality of separate and unconnected address plates, and coöperating means for actuating the impression roller 15 and for moving the address plates from the magazine to printing position.

13. In an addressing machine, the combination of a bed, an impression roller adapted to bodily travel thereover, a magazine 20 adapted to contain a plurality of separate and unconnected address plates, and coöperating means for actuating the impression roller and for moving the address plates from the magazine into printing position 25 in a direction transverse to the path of travel of said impression roller.

14. In a printing and addressing machine, the combination of a bed having a type form, an impression roller adapted to 30 bodily travel thereover, a magazine adapted to contain a plurality of separate and unconnected address plates, a guideway extending from the end of the magazine across the bed, and coöperating actuating means

for both actuating the roller and for successively feeding the address plates from the magazine along the guideway to printing position. 35

15. In a printing and addressing machine, the combination of a bed having a type 40 form, an impression roller adapted to bodily travel thereover, a magazine adapted to contain a plurality of separate and unconnected address plates, means for actuating the impression roller, and feeding 45 means acting in conjunction with the roller-actuating means adapted to successively move the address plates from the magazine to a definite position with reference to said type form, and thence beyond said position. 50

16. In a printing and addressing machine, the combination of a bed having a type form, an impression roller adapted to bodily travel thereover, a magazine adapted to contain a plurality of separate and unconnected address plates, a guideway extending from the magazine across the bed, means for actuating the impression roller, and means for feeding address plates from the magazine along said guideway to two 55 successive separate printing positions, and thence from said guideway. 60

In testimony whereof, I hereunto affix my signature in the presence of two witnesses.

EDWARD G. ERNST.
